CERAMIC REED RELAY HAVING FLUX CARRYING MEANS ASSOCIATED WITH THE ARMATURE

Edward Ronald Myatt, Redbourn, and Ernest Frederick Loveland, London, England, assignors to International Standard Electric Corporation, New York, N.Y., a corporation of Delaware

Filed Aug. 1, 1966, Ser. No. 569,176

Claims priority, application Great Britain, July 30, 1965, 32,743/65

14 Claims. (Cl. 335—151)

The invention relates to electromagnetic relays of the kind having their contact making members hermetically sealed inside an enclosure and especially to relays having a flat armature employed as a contact member.

According to the invention there is provided a sealed contact assembly having two members of ferromagnetic material, which members are spaced apart and project into a sealed enclosure of electrically insulating material, each of the members having a contact carrying portion, which members overlap each other at least over their respective contact carrying portions, said assembly thereby having a fixed contact provided by one of said members, and an armature provided by the other one of said members, the application of flux to said members causing said armature to engage with said fixed contact, and including flux carrying means associated with said armature for increasing the effective flux in the air gap between the armature and said fixed contact.

Embodiments of the invention will now be described with reference to the accompanying drawings, in which:

FIG. 1 is a sectional side elevation of a contact assembly;

FIGS. 2A and 2B show an armature and a flux carrying member associated therewith, according to the invention, which are incorporated in a contact assembly of the type shown in FIG. 1;

FIGS. 3A and 3B are respectively a plan view of a rectangular plate and armature, and a sectional side elevation of a contact assembly incorporating the armature;

FIG. 4 is a side view of a modified armature arrangement, according to the invention, and an associated fixed contact;

FIG. 5 is a sectional side elevation of a double-make contact assembly;

FIG. 6 is a sectional end elevation of two double-make contact assemblies;

FIG. 7 is a side view of a further contact assembly;

FIG. 8 is a side elevation of a change-over contact;

FIGS. 9A to 9C show different contact arrangement which incorporates armature backstops;

FIGS. 10A to 10C show respectively a plan view, side elevation and end elevation of a modified armature and associated fixed contact;

FIGS. 11A and 11B show the armature arrangement of FIG. 4 applied to two further contact arrangements.

Referring to FIG. 1, a contact assembly has an annular plate 1 of ferromagnetic material with an armature 2 formed from an integral with the plate. The armature 2 has a portion at its unconnected end acting as a movable contact member. The plate 1 is sandwiched between two caps 3 and 4 of electrically insulating material. A ferromagnetic rod 5 has one end 6 extending through the end cap 4 to provide a fixed contact and magnetic pole piece. The contacts are hermetically sealed inside the enclosure formed by the internal recesses of the end caps 3 and 4. For operating the contacts an energizing coil (not shown) can be wound round the rod 5, with electrical connection made to the contacts via the rod 5 and upstanding portion of the plate 1. The end caps 3 and 4 are preferably made

2

of a ceramic material as also in the embodiment to be described with reference to FIGS. 4, 5 and 6.

Where it is important that the contact assembly should be as small as possible it is difficult to give an armature a sufficiently high degree of flexibility not to adversely affect the operating characteristics of the assembly.

FIGS. 2A and 2B show a short linear armature 2 whose flexibility is enhanced by reducing its cross-sectional area in the region of its fixed end. The armature is reduced in thickness over a portion of its length indicated by the hatched lines to produce a groove 12 across its width. An annular member 13 of ferromagnetic material of low reluctance is placed against one side of the plate preferably the grooved side. The member 13 is shaped to overlap at 14 the grooved portion of the armature and is spaced from it. The member 13 compensates for the restriction to the flux path due to the groove 12.

FIGS. 3A and 3B show a contact assembly having a rectangular plate 23 of ferromagnetic material hermetically sealed between two caps 24 and 25. The caps form an enclosure for an armature 26 and a fixed contact 27 on the end of a ferromagnetic rod 28 hermetically sealed into the cap 25. In this arrangement the armature 26 is parallel to the longer sides of the diaphragm and is as long as is conveniently possible. Thus the length of the armature is about equal to the longer dimension of the diaphragm.

Increased flux in the gap between the fixed contact member and the adjacent portion of the armature is obtained in the manner illustrated in FIG. 4 in which a member 29 of magnetic material is secured to the fixed end of the armature 26 and extends its length to overlap the armature at its free end. The member 29 provides a further path for the flux leaving the contact carrying portion of the armature.

FIG. 5 shows an assembly having two make contacts. A further rectangular plate 30 of ferromagnetic material is spaced from the plate 23 by a spacer 31 of electrically insulating material. Integral with the diaphragm 30 is an armature 32 having a contact portion at its free end aligned with a fixed contact 33 carried on a rod 34 hermetically sealed into the cap 24. If several assemblies each having two make contacts are arranged side by side to form a multiple contact device then, as shown in FIG. 6, the spacer 31 can be made common to all the assemblies. The spacer 30 in the constructions as shown in both FIGS. 5 and 6 is made of ferrite so as to increase the effective flux in the gap between the fixed contact members and the adjacent portion of the associated armatures, and so perform the function of the member 29 shown in FIG. 4.

As another alternative to the member 29, one of the end caps of the enclosure can be utilized for the purpose. The assembly illustrated in FIG. 7 has a ceramic end cap 38 and an end cap 39 of ferrite material which is electrically insulating. The end cap 39 could be made of a conductive ferromagnetic material which would then be spaced from the plate by a spacer member of electrically insulating material.

As illustrated in FIG. 8, the rectangular plate type contact assembly can be modified to operate as a change-over contact. A rectangular plate 43 is sandwiched between two ceramic end caps 44 and 45. The armature 46 is normally urged against a contact member 47 of non-magnetic material. The application of magnetic flux to the assembly attracts the armature 46 to a second contact member 48 of ferromagnetic material. In order to ensure that the armature is urged against the member 47 with the required contact pressure, the contact bearing end of the member 47 is set to protrude beyond the plate contacting face of the cap 44 by a distance d , which is the amount by which the end of the armature 46 must be displaced

to exert the required contact pressure against the member 47. The end of the member 48 is set short of the diaphragm contacting face of the cap 45 by a distance of $d+g$, where g is the required distance between the armature and the member 48 when the armature is in its rest position. Therefore, when the plate and caps are secured together, the armature is initially displaced by the member 47 towards the member 48 a distance equal to d and thus in its rest position remaining a distance g from the end of the member 48. To improve the operating sensitivity in the manner previously described with reference to FIG. 7, the cap 44 could be made of either ferrite or ferromagnetic material. In the latter case, however, it would be necessary to electrically insulate the plate from the cap 44 by a spacer member of electrically insulating material.

In the case of the previously described single and double plate assemblies a back stop can be provided which is engaged by the armature on its return to its rest position to shorten the period during which the armature vibrates before coming to rest. FIGS. 9A to 9C illustrate various of the previously described constructions with a back stop provided. FIG. 9A has a ferrite cap 49 which has a back-stop in the form of a stud 50 which is secured to the recessed face of the cap. In the released position the armature 51 rests against the stud 50. The assembly of FIG. 9B has a ferromagnetic cap 52 which is provided with an indent 53 which serves as the back stop for the armature 54. The assembly of FIG. 9C has two plates 55 and 56 separated by a ferrite spacer 57. In this case the back-stops are in the form of studs 58 and 59 which are located on opposite sides of the spacer 57. In each of the constructions just described, the back-stop protrudes towards its armature sufficiently far for the armature to normally occupy a position nearer to the fixed contact than would otherwise be the case.

To reduce the likelihood of faulty operation of the contact assembly due to the contacts making poor electrical contact with each other, the armatures of the previously described plates and their respective fixed contacts may be modified as illustrated in FIGS. 10A to 10C by providing a cylindrical end 60 to the fixed contact and a slot 61 in the free end of the armature. The end of the fixed contact has the axis of its cylindrical end across the width of the armature. When the contacts close the two portions 62 and 63 of the armature on either side of the slot 61 are attracted independently of the armature makes poor contact there is a good possibility that a low resistance make between its other portion and the fixed contact will exist.

The features which have been described above relating to an improvement in the flexibility of the relay armature and to the provision of additional flux carrying means associated with the armature are not intended to be confined to contact assemblies having rectangular diaphragms nor necessarily to assemblies of the construction illustrated in FIG. 1. In general these features are applicable to contact units of the type in which at least two so-called reeds are sealed into an enclosure of insulating material, e.g., glass, which is evacuated or filled with an inert gas. One or both of the reed contacts is or are of ferromagnetic material so that the application of magnetic flux thereto causes contact operation. FIGS. 11A and 11B illustrate two typical sealed contact units of the type just described in which a movable member 70 is reduced in thickness at its contact bearing end 71 for enhancing its flexibility. A magnetic member 72 is secured to the member 70 at its fixed end either inside or outside the enclosure 73. The member 72 serves the same purpose previously described for the member 29 of FIG. 4.

It is to be understood that the foregoing description of specific examples of this invention are made by way of example only and are not to be considered as a limitation on its scope.

What is claimed is:

1. A sealed contact assembly having two members of ferromagnetic material, which members are spaced apart and project into a sealed enclosure of electrically insulating material, each of the members having a contact making portion, which members overlap each other at least over their respective contact making portions, said assembly having a fixed contact provided by one of said members and an armature provided by the other one of said members, the application of flux to said members causing said armature to engage with said fixed contact, flux carrying means associated with said armature for increasing the effective flux in the air gap between the armature and said fixed contact, said member forming said armature being a strip-like member which is reduced in thickness over a portion of its length including its contact carrying portion, and including a member of ferromagnetic material secured to the armature member between its fixed end and the portion of reduced thickness,
- 5 10 15 20 25 30 35 40 45 50 55 60 65 70 75 80 85 90 95
2. A sealed contact assembly for a light current electromagnetic relay including a first member of ferromagnetic material in the form of a flat annulus having a tongue-like armature formed from and inwardly projecting therefrom to provide a movable contact member, the fixed end of the armature having a portion of reduced thickness, a second member of ferromagnetic material of low reluctance in the form of an annulus dimensionally similar to said first member, which second member has an inwardly projecting portion overlapping and spaced from the portion of the armature of reduced thickness, a cap of electrically insulating material sealed on each side of said first and second members to form therewith a hermetically sealed enclosure between the caps, the interior surface of at least one of the caps being spaced from said armature to allow for its movement, and a rod of ferromagnetic material hermetically sealed through the last mentioned cap to provide a fixed contact member and magnetic pole piece co-operating with the movable contact member.
3. A sealed contact-assembly for a light current electromagnetic relay including a flat rectangular plate of ferromagnetic material, an armature formed from and integral with said plate, a cap of electrically insulating material sealed on each side of said diaphragm to form therewith a hermetically sealed enclosure between the caps, the interior surface of at least one of the caps being spaced from said armature to allow for its movement, and a rod of ferromagnetic material hermetically sealed through the last mentioned cap to provide a fixed contact member and magnetic pole piece co-operating with the movable contact member, and including flux carrying means carried by said armature for increasing the effective flux in the air gap between the armature and said fixed contact.
4. An assembly as claimed in claim 3, in which the armature extends in the direction of the longer pair of sides of the rectangular plate and is at least almost equal to the length of said sides.
5. An assembly as claimed in claim 3, in which the cap retaining the fixed contact member is of ceramic material, and the opposite cap is of ferromagnetic material which provides said flux carrying means carried by said armature.
6. An assembly as claimed in claim 3 and including a further fixed contact member of non-magnetic material hermetically sealed through the opposite cap to that which carries said rod of ferromagnetic material, the interior

surface of both said caps being spaced from said armature to allow for its movement, said armature being normally spring urged into contact with said further fixed contact member and in which said opposite cap is of ferromagnetic material which provides said flux carrying means associated with said armature.

7. An assembly as claimed in claim 5, wherein said opposite cap is of ferrite material.

8. An assembly as claimed in claim 5, wherein said opposite cap is of conductive ferromagnetic material, 10 which cap is spaced from said plate by a spacer member of electrically insulating material.

9. An assembly as claimed in claim 3 including a further rectangular plate of ferromagnetic material dimensionally similar to the first mentioned plate, the two plates being arranged parallel to each other and spaced apart by a member of ferrite material, each plate having sealed to one side thereof a different one of said caps, both caps having an internal surface spaced from the adjacent armature, and a further rod of ferromagnetic material hermetically sealed through the opposite cap to said last mentioned cap to provide a fixed contact member and magnetic pole piece co-operating with the movable contact member of the further plate, wherein the member of ferrite material provides said flux carrying means associated with each armature.

10. An assembly as claimed in claim 9, wherein the plates are arranged with their movable contact members common to one end of said enclosure.

5

11. At least two assemblies as claimed in claim 9 arranged side by side wherein said member of ferrite material is common to each of said assemblies.

12. An assembly as claimed in claim 5 wherein said opposite cap is provided with a back-stop for said armature, which stop is engaged by the unconnected end of said armature when the armature occupies its released position.

13. An assembly as claimed in claim 9, wherein said member of ferrite material is provided with a back-stop for each said armature, which stops are provided on opposite sides of the member, each of which stops is engaged by the unconnected end of the associated armature when said armature occupies its released position.

14. At least one assembly as claimed in claim 2, wherein in each said armature is provided with a slit parallel to the sides of the armature and extending from its unconnected end, and wherein the fixed contact associated with said armature has a cylindrical end thereto whose axis is arranged across the width of said armature.
